UNITED STATES PATENT OFFICE.

MARY MARSTON, OF OMAHA, NEBRASKA.

DESIGN FOR A STATUETTE, WATCH-FOB, EMBLEM, BADGE, RADIATOR-CAP, OR AN ARTICLE OF SIMILAR NATURE.

58,608.

Specification for Design.

Patented Aug. 2, 1921.

Application filed January 10, 1921. Serial No. 436,359. Term of patent 7 years.

To all whom it may concern:

Be it known that I, MARY MARSTON, a citizen of the United States, residing at Omaha, in the county of Douglas and State of Nebraska, have invented a new, original, and ornamental Design for Statuettes, Watch-Fobs, Emblems, Badges, Radiator-Caps, or Articles of Similar Nature, of which the following is a specification, reference being had to the accompanying drawing, forming part thereof.

The figure is a view of a statuette, showing my design.

I claim:

The ornamental design for a statuette, watch fob, emblem, badge, radiator cap, or article of similar nature, substantially as shown.

MARY MARSTON.
